TELESCOPIC SIGHT MOUNT FOR FIRE ARMS

Ernesto P. Dillon, Buenos Aires, Argentina

Application December 13, 1955, Serial No. 552,926

4 Claims. (Cl. 33—50)

The present invention refers to a telescope sight mount for firearms, the object of which is to provide a new lock mounting of the telescope sight which in the manner it is combined with the rifle or weapon carrying it without any supporting bases, constitutes an important innovation in this sort of optical instrument which greatly benefits marksmen in general.

Towards this end many mount systems have been proposed, and it may be said that they have proved beneficial in every sense. However the result of same is not what has been expected in practice, as the mount sustaining the sight piece requires, in most cases, another mount as base for the gun, which means that in each rifle model a special structure is required which complicates in a great measure its application, as the shapes, dimensions and exterior forms of the arms vary fundamentally between each other, in accordance with the manufacturing plant producing them.

This means that for each model a special base piece or pieces are required to be made, in order to the device being affixed with screws or other means in such a manner that they remain fixed to the body enclosing the mechanism in contiguity to the latch. Said pieces, in turn, must possess the means for adapting the carrying sight mount, which logically requires a proportional co-ordination in the mounting with the consequent registry for correcting errors in the alignment with respect to the sight at the extreme end of the barrel.

The fact of having to fix the base pieces for the sight mount tends to show other disadvantages which specially alter the practice of the use of fire-arms, for, if the sight mounting is taken away, there always remains the base pieces which generally annul the direct sight. It may therefore be said that the gun or rifle is disabled in order to take aim if the telescopic sight is not mounted.

Worthy of mention is the manner in which the system of the present invention avoids all these inconveniences above mentioned, as, comprising a mounting proper, with all its parts for the fixing of the telescope constituting the sight, it dispenses of all additional bases for its mounting on the fire-arm; that is to say that, it consists in the appliance of the mount in a direct manner.

To this end the mount possesses on one hand a set of projections which coincide with recesses made in the interior of the opening of the receiver box, whilst on the other hand, said mounting possesses at least one tooth of the latch type, pressed by a spring coinciding with a catch formed in the interior of said opening of the receiver box, but on the opposite side of the recess, so that said latch-tooth may be wedged in the corresponding catch in order that with a simple maneuver, all the points of the mount may be fixed in the corresponding means; with this direct setting, the fire-arm is ready to be operated, with the telescopic sight in the most precise manner which may be conceived, as the position of the mount is determined by the proper projecting means in direct form; and since the recesses are made in accordance with the position of the pro-

2

jections and latches of the sight, the position is then precise as if the mount were part of the fire-arm, applied in the factory, all of which with the advantage of being easily removable, so that the exclusion of the sight and its mount leaves free the sight system of the fire-arm as, by not leaving any fixed piece with screws, the direct aim of the fire-arm may be employed.

For a greater clearness of the object of this invention, same has been illustrated with several drawings in which:

10 Fig. 1 is a part of a rifle or fire-arm which shows the part of the opening corresponding to the receiver; the front and posterior part of said opening has been partially sectioned so as to show the recesses and retention for the plugs and latch tooth of the mount carrying the sight;

15 said mount has also been sectioned in partial manner so as to show the slider of the latch, which is pressed by a spring.

Fig. 2 is a view below, represented in section, so as to show the safety screw of the latch in order to maintain 20 in fixed manner the retaining of the mount.

Fig. 3 is the mount seen in profile, frontwise, in such a manner that the disposition of the plugs may be seen. Such disposition may change slightly according to different fire-arms.

25 Fig. 4 is a lateral view of a fire-arm, the corresponding opening of the receiver showing with partial sections the front and rear of the recess in which enter the plugs and latch teeth of the mount. Same is shown as set and carrying a telescopic sight.

30 Fig. 5 is the tooth of the latch of a different type which, instead of a sliding device, possesses a lever pressed by a spiral spring. Finally:

Fig. 6 is the tooth of the latch also as a lever as in Fig. 5 but with a rigid spring.

35 In the different drawings the same reference numbers indicate equal or corresponding parts, the different components being indicated by letters.

As may be seen in the drawings, *a* is the breech mechanism action where the breech lock bolt is commonly placed. Such breech mechanism *a* possesses an opening 40 1 which constitutes the access to its interior and laterally serves as outlet for the spent cartridges.

This means that it belongs to a rifle or fire-arm of the known types to which must be applied the sight *b* with its mounting *c* possessing the novelty characteristics for its application in direct engagement.

Mounting *c* has two clasps 2 and 3 which hold the telescope of sight *b*. As the mount is destined to be applied in direct manner to the fire-arm, it possesses in the front 50 part of the mount a projection 4, the surface 5 of the lower part being slightly concave so as to be adapted to the convexity of the body 6 which holds the barrel 7 and chamber 8; whilst in the rear part the mount *c* has a resting surface 9 corresponding so as to be adapted to the face 10 of the rear part immediate to the opening 1.

Below the level of surface 5 the mount *c* possesses a spur 11 which affects the form as shown in profile of Fig. 3 and coincides for entering into opening 1, but against the access to the chamber 8. In this spur 11 the mount has one or more plugs 12 directed parallelly to the longitudinal line of the sight, and according to the position of these plugs, the respective recesses 14 are made in the internal border 13 of body 6, with which must coincide plugs 12 when the surface 5 of the projection 4 is adapted 55 against the superior face of body 6.

Furthermore, mount *c* in the opposite side of spur 11 possesses a latch tooth 15 which, being pressed by springs 16 has a displacement with rear tension, so that after yielding to a certain pressure forward is able to be fixed 60 in any catch.

In the rear part of opening 1 a catch 17 is made

adjacent to surface 10, said catch being slanted so as to coincide with the slant of tooth 15; the distance between tooth 15 and the resting surface 9 is related in proportion with the distance comprised between the catch 17 and the face of the base 10, so that if said surface 9 is adapted on the face of the base 10, tooth 15 will be fixed in catch 17; but the fixing of same must be made overcoming the position of spring 16 so that the displacement is sufficient in order to also insert plugs 12 in recesses 14. As shown in Fig. 1, fixing first the tooth-latch 15 in the catch 17 and making certain pressure backwards for a longitudinal displacement, the mount, due to the contraction of spring 16 allows spur 11 to enter the front part of opening 1, so that plugs 12 may be fixed in recesses 14, the mounting being thus engaged in such a manner as shown in Fig. 4, in which through the adjustment of spring 16 the mount is set as if it were an integral part of the breech mechanism; and for greater security it may be fixed with a safety screw 18 which avoids the displacement of latch-tooth 15.

In this manner the fire-arm is provided with an optical sight *b* which is a telescope of the current type which in the position given by mount *c* determines the exact aim-line so as to obtain success in the firing.

In case of necessity, the clasp 2 is adapted to the mounting *c* with a transversal guide of glide tail 19; as may be appreciated in Figs. 1 and 4 this ring is governed by a windage adjusting screw, 20.

With the same ease as it is engaged, mount *c* can be unmounted as, after loosening the safety screw 18 with a slight backward pressure, spring 16 is contracted, liberating plugs 12 from recesses 14, the tooth 15 remaining in condition to being freed from catch 17; so that the sight and its mount are separated from the fire-arm, which may be used without the optic sight.

In the examples of Figs. 1, 2 and 4 the tooth latch has a slide *d* which slides in guide 21 where also is included a spring 16; on the other hand, in the examples of Figs. 5 and 6 the tooth latch 15 is united to lever *e* with fulcrum in the pin 22 and its arm 23 which is pressed by spring 16.

In the example of Fig. 5 spring 16 is helicoid whilst in Fig. 6 the spring is rigid. Undoubtedly when carrying out this invention, modifications in construction may be introduced, without this implying a departure from the fundamental principles of the claims which follow.

I claim:

1. Telescopic sight mount for fire-arms, comprising a rigid piece constituting a mounting disposed parallel to the axis of the sight and provided at its extremities with two spaced clasps for holding the telescopic portion of the sight, a set of projections at the forward end of the mounting extending in the direction of fire and interfittable with corresponding grooves formed in the internal front end of the opening corresponding to the breech action mechanism of the fire-arm, a latch at the rear end of the mounting spring pressed toward the butt end of the fire-arm and cooperating with a catch at the rear end of said breech opening, whereby said rigid mounting is

adapted to be directly and removably engaged in the opening of the breech action mechanism.

2. Telescopic sight mount for fire-arms, comprising a rigid piece constituting a mounting disposed parallel to the axis of the sight and provided upon its ends with two clasps which form an integral setting with said mounting for holding the telescopic portion of the sight, a spur at the front end of said mounting provided with two plugs extending parallel to the fire-arm and projecting in the direction of fire, said plugs registering with recesses in the internal front end of the opening corresponding to the breech action mechanism, a latch of wedge form at the rear end of the mounting spring pressed under tension towards the butt end of the fire-arm, said latch cooperating with a catch in the rear of said breech opening, whereby said mounting is adapted to be directly engaged in the opening of the breech action mechanism.

3. Telescopic sight mount for fire-arms, comprising a rigid piece constituting a mounting disposed parallel to the axis of the sight and provided upon each extremity with a clasp to form an integral setting with said mounting for holding the telescopic portion of the sight, said mounting at its forward end being provided with a two plug spur parallel to the fire-arm and projecting in the direction of fire, said plugs registering with complementary recesses in the internal front end of the opening corresponding to the breech action mechanism, and said mounting being provided at its rear end with a latch of wedge shape forming part of a backwardly spring pressed tension, said latch cooperating with a catch in the rear end of said breech opening, whereby said mounting is adapted to be directly engaged in the said opening of the breech action mechanism.

4. Telescopic sight mount for fire-arms, comprising a rigid piece constituting a mounting disposed parallel to the axis of the sight and provided on its extremities with spaced clasps to form an integral setting with said mounting for holding the telescopic portion of the sight, said mounting at its forward end being provided with a spur having two plugs projecting in parallel toward the direction of fire, said plugs registering with corresponding recesses in the internal front end of the opening corresponding to the breech action mechanism, the mounting at its rearward end being provided with a latch of wedge shape forming part of a lever pressed by a spring with butt-end tension, said latch cooperating with a catch in the rear end of the said opening, whereby said mounting is adapted to be directly engaged in the said opening of the breech action mechanism.
